WING PLOW STRUCTURE

George L. Kaeser, Hartford, Conn.

Application March 14, 1947, Serial No. 734,575

1 Claim. (Cl. 37—42)

1 My invention relates to improvements in wing plow structures for vehicles, of a type adapted to lie laterally at an oblique angle on the side of a vehicle to push the snow, dirt or other substance to be removed laterally as the vehicle moves forward. While I am aware that wing trips have been employed hitherto in snow plows, so far as I am aware they have always been employed in association with a plow for the front of the vehicle such as a mold board plow and the wings have usually been mounted on the rear ends of the plow itself without trips.

A main object of my invention is to rigidly mount the wing on the vehicle entirely independently of any plow for the front of the vehicle and preferably so that the wing will lie at an oblique angle laterally of the vehicle behind the front wheels. This results in many advantages over mounting it on the plow, in that a more rigid mounting is permitted and that the wing may be raised and lowered independently of the front plow, if employed, so that it may be used without any front plow, if desired, a feature not possible where the wings are mounted on the front plow.

A further advantage of mounting the wing at a spaced distance behind the rear end of the front plow is that a suction is often created by said rear end tending to pile up snow in the vacuum formed by the moving plow, resulting in masses of snow and ice collecting at the point of connection of the wing to the rear end of the plow. With my device, this tendency to mass snow at this point is eliminated. In addition, it is possible to more rigidly mount the wing independently of the front plow so that it may be raised and lowered and swiveled entirely independently thereof and it is also apparent that a wing so mounted is not subject to any shock which may affect the front plow. It is also apparent that inasmuch as a space is left between the rear edge of the plow and wing that the work is split up between two inclined planes with the second having more independent momentum than if it were attached as part of the first inclined plane.

A further feature of this mounting resides in the fact that it is easier to mount the swivelling element thereof on the back of the vehicle so that the wing may be rigidly supported, not only at its pivot point but from the rear.

A further feature of this construction resides in the fact that as the wing is mounted independently of the front plow it may have a wider angle of swivel than that permitted if it is

2 swivelly mounted on the inner edge of the front plow.

5 A further feature of my invention resides in the fact that I employ a hydraulic system to raise and lower the wing on its support or pivot and that I also provide an additional hydraulic system to swivel the wing on its support. This provides a compact system having no exposed cables or parts which tend to become encrusted with snow or ice in use, a system which provides a powerful means for raising and lowering and swivelling the plow and one which is immediately responsive as the movable parts always ride on the oil and are better cushioned thereby in use than if mounted on a rigid portion.

10 A further object of my invention is that I so construct and pivotally yieldingly mount the wing on the frame so that its lower end may pivot or trip inwardly on abutment of a low obstruction, 20 against its lower end, in other words, so that it may readily trip over any low obstruction and be immediately forced back by a return spring to a substantially vertical plowing position. I am able to do this by a new feature of construction by mounting a jib plate so that it may be raised or lowered on a rigid hydraulic mast and also swivel on said mast and I pivotally mount the wing on the outer end of said jib plate so that a cooperating return spring for the wing may be mounted on said wing and jib plate.

25 30 A further feature of my invention resides in the fact that I so construct my improved device that the entire wing may yieldingly swivel inwardly on abutment of a high obstruction against said wing without interfering with the operation of any other part of the plow or vehicle and for this purpose I preferably employ a pressure relief valve in a by-pass line connected only to the swivelling hydraulic cylinder.

35 40 A further feature of my invention is that I provide a wing plow which it is almost impossible to damage, as the wing may trip or tilt on abutment of a low obstruction against its lower edge and be immediately urged to a vertical plowing position after it has passed said low obstruction and the entire wing may yieldingly swivel inwardly on abutment of a high obstruction against said wing.

45 50 Further features of my invention relate to the specific construction of the various parts, including the specific structure of the wing trip, and the means I employ for rigidly mounting the wing and its supporting jib plate on a mast rigidly mounted on the frame of the vehicle independently of the front plow.

These and such other objects of my invention as may hereinafter appear will be best understood from a description of an embodiment thereof such as is shown in the accompanying drawings.

Fig. 1 is a front elevation of a truck chassis equipped with my improved wing plow structure, showing the wing in operating position in full lines, swiveled to a small oblique angle relative to the truck frame, swiveled to an extreme outward position in dotted lines and raised to an upper inoperative position in dash lines.

Fig. 2 is a side elevation of the truck having my invention attached shown in Fig. 1 looking towards the side having a wing thereon.

Fig. 3 is a perspective view looking from the rear towards the wing side of the truck shown in Figs. 1 and 2.

Fig. 4 is a plan view of the truck shown in Figs. 1-3 showing the wing in inoperative position in full lines and in operative outwardly swiveled position in dotted lines.

Fig. 5 is a diagrammatic view of the hydraulic system employed both to raise and swivel the wing.

Fig. 6 is a sectional view taken along the line 6—6 of Fig. 5.

Fig. 7 is a sectional view taken along the line 7—7 of Fig. 5.

Fig. 8 is a sectional view taken along the line 8—8 of Fig. 5.

Fig. 9 is a plan view of the wing trip portions of the jib plate and wing and connecting parts.

Fig. 10 is a diagrammatic end perspective view showing the end of the wing about to pass over a low obstruction.

Fig. 11 is a diagrammatic side elevation similar to Fig. 10, showing how the wing trips or tilts as it passes over said low obstruction.

Fig. 12 is a diagrammatic end perspective view of the jib plate and wing showing its tripping parts and the hydraulic cylinder for swivelling the wing with its connecting pipe, about to abut a high obstruction.

Fig. 13 is a diagrammatic side elevation of the parts shown in Fig. 12, showing how the high obstruction has yieldingly pushed the entire wing inwardly so that it may pass by it without injuring any portion of the wing.

In the drawings, wherein like characters of reference generally indicate like parts throughout, 20 generally indicates a wing plow structure constructed in accordance with my invention. As stated, my invention is adapted to be used in any type of vehicle 22 having a frame 23, but is preferably employed on a self-propelled vehicle such as an automobile truck 22 propelled by a gas engine (not shown).

Broadly, I provide means to raise and lower said wing plow 20, means to swivel said wing plow inwardly and outwardly on a pivot adjacent the front portion of the vehicle in rear of the front wheels 24 and means to yieldingly pivotally mount said wing on said frame, so that its lower end may pivot inwardly or trip on abutment of a low obstruction against its lower edge and/or so that the entire wing may yieldingly swivel inwardly on abutment of a high obstruction against said wing.

To mount said wing 20 on said frame, I rigidly mount a hollow mast 26 on the frame to extend vertically upwardly beside the front portion thereof in rear of the front wheels 24. I provide a jib plate 28 swivelly mounted on said mast and I provide means to raise and lower said jib

plate on said mast, said means being preferably fluid expansible. I also provide means interposed between the rear end of the frame 23 and the outer end of said jib plate 28 to swivel said jib plate inwardly and outwardly, said means being also preferably fluid expansible. The wing 20 is pivotally mounted on the outer surface of said jib plate, so that its lower edge 30 may pivot inwardly and I provide the spring means 32 mounted on said wing 20 and jib plate 28 to normally urge said wing to a vertical position yieldable to permit said pivoting.

I may provide fluid pressure means having the control handle 34 adjacent the driver's seat to 15 actuate said mast fluid expansible means to raise and lower said jib plate 28 and wing 20, and I may provide fluid pressure means having a control handle 36 adjacent the driver's seat to 20 actuate said swivelling fluid expansible means to 25 swivel said jib plate and wing on said mast and as means to permit the entire wing and jib plate to swivel inwardly on the abutment of a high obstruction against said wing I provide a by-pass line 38 connecting said swivelling fluid expansible means to said fluid pressure means, having a pressure relief valve 40 therein to permit excessive lateral pressure against said wing to pivot it inwardly.

While my improved device may be constructed in any suitable manner, it is preferably constructed as follows: I provide the holding mast 26 and rigidly mount it on a rigid base 42 projecting laterally from underneath the frame as shown in Figs. 1 and 2. This may, if desired, be part of the mechanism as shown for mounting a V plow on the same truck or it may be a special separate connection to form a base for rigidly mounting the mast on the vehicle frame. As stated, my improved mast 26 preferably extends vertically upwardly besides the front portion of said frame 23 in rear of the front wheels 24. Said mast has the closed lower end formed by the supporting base plate 42 and a longitudinal slot 44 of a width to extend substantially 90° circumferentially from the outer side to the rear thereof substantially throughout the height of said mast 26. I may, if desired, supply additional means to mount the mast 26 rigidly on said frame such as the guy rod 46 projecting forwardly and downwardly to the front portion 48 of the frame and the side guy rod 50 connected to another rigidly mounted frame portion 52 such as the opposite end 54 of the frame 56 which may be employed for mounting the front plow thereon.

I also may, if desired, provide a lower guy rod 58 connecting the lower end of the mast to a rear portion of the frame 23.

In the preferred embodiment shown I preferably construct the fluid expansible means for raising the jib plate 28 as follows, i. e., as comprising cooperating telescopic Shelby tubing and for this purpose I provide an inverted external cylinder 60 having an open lower end 62 contained within said mast 26, having the jib plate 28 soldered or otherwise secured thereto to project radially therefrom a substantial distance through said slot 44 to swivel back and forth from an outer position near right angles to said frame 23 to an inoperative position adjacent the vehicle frame. Said jib plate has an outer portion 64 of less height than its inner portion (see Fig. 5), having a vertical pivot fin 66 projecting outwardly from adjacent the outer end thereof, a hole 68 therein above said pivot fin and a vertical pivot fin 70 projecting inwardly therefrom.

I also provide an internal supporting cylinder 72 telescopically contained within said external cylinder 60 projecting upwardly from the base 42 of said mast 26, having a radial inlet and exhaust hole 74 aligned with an inlet and exhaust hole 76 in said mast near the base thereof. I also provide a piston 78, vertically reciprocal in said internal supporting cylinder 72, having a piston rod 80 projecting upwardly therefrom to the top of said inverted external cylinder 60, whereby fluid pressure admitted through said inlet holes 76 and 74 may raise said external cylinder 60 and said attached jib plate 28, and the weight of said external cylinder 60 and said attached jib plate 28 may cause said jib plate and cylinder to drop to exhaust fluid through said aligned holes 74 and 76. It is thus apparent that when fluid is admitted inwardly through the holes 76 and 74 that the external cylinder 60 and attached jib plate 28 will be raised and when fluid pressure is released in said holes that said external cylinder 60 and attached jib plate 28 will drop.

In the specific embodiment shown, as the fluid expandable means to swivel said jib plate on said mast 26 as a pivot, I provide an internal cylinder 82 mounted to swivel in a substantially horizontal plane on the rear end of the frame 23 in rear of said hollow mast 26, such as by the pivot hinge 84 shown. Said cylinder has the fluid inlet and exhaust hole 86 adjacent said frame. As a part of said fluid expandable means, I also provide an external cylinder 88 of larger diameter telescopically mounted on said internal cylinder 82, having its closed outer end mounted on said jib plate fin 78 to pivot in a horizontal plane as by the pivot knuckle hinge 90. I provide the piston 92 horizontally reciprocal in said internal cylinder 82 having a piston rod 94 connected to the outer end of said external cylinder 88 and I provide retraction spring means 96 connecting said jib plate fin 78 to the rear portion of said frame 23 near said pivot knuckle 84 to normally pull said jib plate inwardly to inoperative position adjacent the frame whereby fluid pressure admitted through said cylinder hole 86 may pivot said jib plate outwardly and said spring 96 may pivot said jib plate inwardly on drop of pressure within said hole.

The plow wing 20 may have the arcuate outer surface 98 and a vertical fin 100 substantially centrally of its inner surface. I provide means such as the pivot pin 102 to pivotally mount said rearwardly projecting wing fin 100 on said outer jib plate fin 66 so that said wing may pivot vertically on said horizontal pivot 102. I also provide the trip rod 104 pivotally mounted by the pivot pin 106 on the upper end of said wing fin 100 extending inwardly through said jib plate hole 68 and having an abutment such as the nut 108 on its inner end. I provide a trip coil spring 110 interposed between said abutment 108 and said jib plate 28 around said hole 68 to normally urge said trip rod to a position holding the lower end 112 of said wing in a vertical position as shown in Fig. 10, vertically yieldable to a contracted position as shown in Fig. 11 to permit inward tipping or tripping of the lower edge 112 of said wing over an abutment 114 as shown in Fig. 11 when, after it has passed the abutment 114, the spring 110 may again expand to again position the lower end 112 of said wing in a vertical position. I may also provide a lighter counterbalancing spring 116 interposed between said jib plate 28 and trip rod pivot 106.

I have shown in Fig. 5 a composite fluid system which may provide fluid pressure for actuating the fluid expandable means 31 for raising the jib plate 28 and the fluid expandable means 33 for swivelling the wing 20. Said fluid system includes the storage reservoir or tank 120, the pump 122 connected thereto by the pipe 124, the supply and exhaust pipe 126 leading to the inlet holes 74-76 of said mast cylinders, having the manually operated two way valve 128 therein. I also provide a supply and exhaust pipe 129 leading to the inlet hole 86 of said horizontal cylinder, having a manually operated two way valve 130 therein. As stated, said valves 128 and 130 each preferably have the handles 34 and 36 respectively adjacent the driver's seat. Each valve 128 and 130 has an inlet vent 132 and 134 respectively connected by a common pipe 136 to the pump 122. Each valve 128 and 130 also has an outlet vent 137 and 138 respectively connected by a common pipe 140 with the respective connecting pipe 142 and 144 to the storage reservoir 120. It is thus obvious that by moving the valve 34 in line with the inlet vent 132 that fluid pressure will be admitted to the expandable means 31 of the mast to raise the mast cylinder 60 and its connected jib plate 28 and wing 20 upwardly and when it is moved to be connected respectively to its outlet vent 137, the weight of the jib plate 28, wing 20 and cylinder 60 will force the fluid out through the pipe 126 and through the outlet vent 137 of said valve 128 through the pipes 142 and 140 to the storage reservoir 120 as said cylinder 60, jib plate 28 and wing drop.

It is also obvious that when the handle 36 brings the valve 130 opposite the inlet vent 134 that pressure will be introduced through the pipe 129 through the hole 86 in the inner portion of the cylinder 82 to actuate the piston 92 to swivel the wing 20 and jib plate 28 on the mast 26 as a pivot so that when the handle 36 is turned to bring the valve duct in alignment with the outlet duct 138 that the spring 96 will urge the cylinder 88 inwardly to force fluid outwardly through the hole 86, pipe 129, exhaust duct 138 and pipes 144 and 140 to the reservoir or tank 120.

I also provide the by-pass pipe 38 directly connecting said horizontal cylinder pipe 129 to the storage reservoir 120. Said pipe has an adjustable pressure relief valve 40 therein settable to exhaust therethrough at any desired pressure, whereby as shown in Figs. 12 and 13, should any high obstruction such as the obstruction 150 shown therein abut the wing 20, it will urge the wing 20, the jib plate 28 and the expandable means 33 inwardly to the position shown in Fig. 13, so that said wing may swing past said obstruction 150 without injury to any parts thereof.

It is understood that my invention is not limited to the specific embodiment shown and that various deviations may be made therefrom without departing from the spirit and scope of the appended claim.

65 What I claim is:

In a wing plow construction, a vehicle having a frame and front wheels, a vertical mast on said frame at the side thereof to the rear of said front wheels, an elongated horizontal strut having one end mounted on said mast for vertical movement there along and pivoted thereto for horizontal swinging of said strut relative to said frame, an elongated plow blade mounted on the other end of said strut for pivotal movement 70 about a horizontal axis parallel to the lower edge 75

of said blade, means for yieldingly holding said blade in plowing position but permitting movement rearwardly of the lower edge of said blade upon overload when said blade meets with an obstruction lower than the pivotal axis of said blade, a hydraulically operable system connected between said frame and said strut, said system having means for horizontally swinging said strut and blade outwardly into plowing position at a substantial angle to said frame, and means in said system permitting said strut and blade to swing inwardly upon overload when said blade meets with an obstruction higher than the pivotal axis of said blade, said last-named means including a by-pass and relief valve.

GEORGE L. KAESER.
